UNITED STATES PATENT OFFICE

1,938,097

ELECTRIC FUSE

William F. Curlee, Houston, Tex.

Application October 16, 1931. Serial No. 569,146

2 Claims. (Cl. 200—134)

This invention relates to electric fuses.

It has for its general object the provision of a device including a fuse holder associated with terminal members so that the fuse may readily be placed in and removed from the circuit, the holder embodying new and improved means to releasably hold the fuse so that it may be easily replaced.

Other objects will hereinafter appear.

10 The preferred embodiment of the invention is illustrated by the accompanying drawing, of which Fig. 1 is a longitudinal sectional view of the device showing the fuse in the circuit; Fig. 2, a view similar to Fig. 1, illustrating the movement of the fuse out of the circuit; Fig. 3 is a transverse section on the line 3—3 of Fig. 1; and Figs. 4 and 5 are transverse sectional views illustrating the movement of the blade of the fuse into the clip of the holder.

20 In the drawing, the box or other support in which the device is mounted is indicated at 1. It may have a cover 2. Within the box 1 is mounted an insulating base 3, and on the base 3 are mounted the terminal members 4 and 5 to which 25 the electric wires, not shown, are connected by conventional means. Each of the terminals 4 and 5 has a pair of spaced spring fingers 6. Pivotally mounted at 8 in the box 1 is a fuse holder 9, made of insulating material. Mounted on the 30 holder 9 by suitable bolts 10 are a pair of spaced fuse clips 11. Each of the clips 11 comprises a hook 12 having an elongated flat edge 13; and a spring 14 adjacent the edge 13.

The fuse is shown at 15. It has a pair of blades 35 16.

It will be apparent from the drawing and the foregoing description, that the fuse 15 is placed in the holder 9 by forcing the blades 16 between the hooks 12 and springs 14 of the clips as shown 40 by Fig. 4; that the blades 16 will be firmly held against the edges 13 of the hooks 12 by the springs 14; and that the fuse may quickly and easily be removed from the holder by forcing the blades out of engagement with the hooks 12 45 against the resistance of the springs 14.

It will be noted in Fig. 3 that the edge 13 of the hooks and the contact surfaces of the fingers 6 of the terminals are in substantially the same plane, so that the blades 16 are guided by the holder 9 for movement between the fingers 6 of the terminals 4 and 5.

When the electrician desires to insert a new fuse, he need only remove the cover 2 of the box, swing the fuse holder 9 outwardly on its pivot 8 to move the old fuse away from the terminals 4 and 5, insert a new fuse in the holder, swing the holder back to move the new fuse into the circuit, and replace the cover 2.

I claim:

1. The combination of a pair of electric terminal members, each of said members comprising a pair of spring fingers having flat contact surfaces; a fuse holder having a pair of clips, each of said clips comprising a hook having an elongated edge, and a spring adjacent said edge; and a fuse having a pair of blades forcible between the springs and hooks of said clips to be releasably held by said springs against the flat edges of said hooks; a support for said terminals and holder; said holder being pivotally mounted on said support so that it may be swung on its pivot to force said blades between and to remove said blades from the contact surfaces of the fingers of said terminal members.

2. The combination of a pair of electric terminal members, each of said members comprising a pair of spring fingers; a fuse holder having a pair of clips, each of said clips comprising a hook having an elongated flat edge, and a spring adjacent said edge; and a fuse having a pair of blades forcible between the springs and hooks of said clips to be releasably held by said springs against said edges of said hooks; said fuse being movable by said holder to force said blades between and to remove said blades from the fingers of said terminal members.

WILLIAM F. CURLEE.
